UNITED STATES PATENT OFFICE.

MARSHALL B. LLOYD, OF MENOMINEE, MICHIGAN, ASSIGNOR, BY MESNE ASSIGNMENTS, TO HEYWOOD-WAKEFIELD COMPANY, OF BOSTON, MASSACHUSETTS, A CORPORATION OF MASSACHUSETTS.

REED ARTICLE AND METHOD OF PRODUCING SAME.

1,412,623.

Specification of Letters Patent. Patented Apr. 11, 1922.

Application filed August 20, 1920. Serial No. 404,793.

To all whom it may concern:

Be it known that I, MARSHALL B. LLOYD, a citizen of the United States, and a resident of Menominee, county of Menominee, and 5 State of Michigan, have invented certain new, useful, and Improved Reed Articles and Methods of Producing Same, of which the following is a specification.

My invention relates generally to the production of reed articles which are of curved or arch-like form but relates more particularly to the production of such articles from flat fabric.

The general object of my invention is to 15 provide a method whereby such articles can be produced rapidly at low cost and by unskilled workmen.

Another object of my invention is to provide a curved, arch-like or canopy-like 20 article which shall be of improved appearance, and which shall be of light and durable character.

My invention consists generally in the 25 steps, acts and stated sequence thereof, and in the article of manufacture resulting therefrom, whereby the above named objects, together with others that will appear hereinafter, are attainable; and my invention will be more readily understood by reference to the accompanying drawings which 30 illustrate what I consider at the present time to be the preferred embodiment thereof.

In said drawings:

Fig. 1, is a view of a strip of reed fabric, 35 which I have chosen for embodiment in the article.

Fig. 2, shows the fabric of Fig. 1 trimmed or cut as one of the steps in the production of the article.

40 Fig. 2^A is a perspective view of a metallic strip used for attachment to the fabric.

Fig. 3, is a diagrammatic view illustrating a further step in the operation.

Fig. 4 is a view similar to Fig. 3 but illustrating a further step in the operation of treating the fabric.

Fig. 5, is an enlarged detailed sectional view substantially on the line 5—5 of Fig. 4.

50 Fig. 6 is a view illustrating the step of firmly securing metallic strips to opposite edges of the fabric.

Fig. 7 is a perspective view of the article frame to which the fabric is to be applied.

Fig. 8 illustrates one step in the placement of the fabric over the frame shown at Fig. 7. 55

Fig. 9 is a view looking at the under side of the completed article; and

Fig. 10, is a perspective view of a child's vehicle, the canopy of which embodies my invention. 60

I have chosen to illustrate the manufacture of a canopy such as is used extensively for children's vehicles of the stroller type, but this, it should be understood, is by way of illustration and not by way of limitation. 65

Referring again to the drawings, 1, represents a piece of reed fabric composed of spaced stake members 2, and the intertwined filler strands 3. This fabric may be produced in any desired manner, but I prefer to weave in large pieces and then to sever a piece of desired length therefrom as this simplifies and cheapens the production thereof. As a next step I cut away opposite end portions of the fabric along the curved lines 75 indicated at 4 in Fig. 2, the cut away portions being made generally in the direction in which the stakes extend rather than in the direction in which the filler strands extend. That is to say, the edge formed by the filler strand ends are cut away. Having thus produced a piece of flat fabric with the curved end portions as shown in Fig. 2, I next take steps to make the curved end portions conform substantially to a straight line 80 between the points 5 and 6. After getting the fabric in this condition I take steps to hold it against its natural tendency to revert to its former curved condition. To this end one of the curved ends 4 may be placed in 85 the U-shaped metallic strip portion 6, shown in Fig. 2^A, and which is of a size sufficient to permit free movement of the fabric therein, i. e., before it is closed on the fabric. I now apply pressure edgewise of the fabric 90 in the direction of the metallic strip and this serves to straighten the curved edge 5. The fabric shifts as may be necessary for this operation, in the loosely fitting metallic member 6. This straightening of the end 100 or edge 4 is accompanied by the bowing outwardly of that end portion of the fabric so that it is formed out of its plane of weave. This operation can be conveniently performed by placing the strip and fabric in 105 the metal forming machine 7 shown in Figs.

3 and 4. When sufficient force has been applied edgewise of the fabric to straighten the edge then the metal forming machine 7 is actuated to bend the metal edge 6 and the fabric to the form shown in Fig. 5. Thereafter the fabric is reversed and the opposite curved edge portion is placed in a similar metallic strip portion 6 and pressure is applied edgewise of the fabric to straighten the remaining curved edge portion. The result of these operations is to straighten both of the curved end portions and to transform the initial flat fabric into a fabric which is transversely curved. If desired, the metallic edges may be placed upon a block 8 (see Fig. 6) and there hammered or otherwise more tightly closed.

The next operation is that of securing the curved fabric to the frame member shown in Fig. 7. To this end the fabric may be secured along one frame member 9 as by placing one of the metallic strip portions 6 thereon and driving brads or other fastening devices through the strips and in the frame. As a matter of convenience in operation the frame is preferably mounted upon a pedestal 10 which is provided with a hand swinging clamp member 11', whereby the opposite edge portion may be forced to meet the opposite frame member 11, at which time the metallic strip can be secured thereto. It is now an easy matter to secure the end portions 12 of the fabric to the end frame members 13, as by means of tacks, brads or other suitable fastening devices. The finished canopy, as will be seen by reference to Fig. 10, is of pleasing form, indeed. The filler strands and stakes are shaped along curved lines that add to the beauty and symmetry of the article.

From the foregoing it is evident that an arched canopy can be formed by my method from a piece of flat strip stock in a simple, quick and easy manner, all by means of unskilled labor, and that the objects and purposes outlined in the specification are secured by the method stated. The many advantages of my invention will be apparent to those skilled in this art without further comment.

I claim:

1. That improvement in the art of manufacturing articles of reed fabric which consists in providing a sheet of such fabric; applying varying degrees of endwise pressure to different portions thereof, thus forcing the fabric out of the plane of weave producing a bowing out of the fabric in both directions and securing the fabric so that it remains in the position to which said pressure has brought it.

2. That improvement in the art of manufacturing articles of reed fabric which consists in providing a sheet of such fabric; applying varying degrees of endwise pressure to different portions thereof, thus forcing the fabric out of the plane of weave producing a bowing out of the fabric in both directions, and in applying metal binding strips to those edges of the fabric to which pressure was applied, thereby securing the fabric against reversion to its reformed condition.

3. The method of producing a reed canopy or the like that consists in providing a piece of reed fabric, holding the fabric against movement as a whole, applying varying degrees of pressure edgewise thereof and thereby moving part of the fabric out of its plane of weave and into substantially concavo-convex form, applying varying degrees of pressure edgewise to the fabric in an opposite direction thereby moving the other part of the fabric out of its plane of weave and into substantially concavo-convex form, and in holding the fabric against reversion to its initial shape by applying metal strips to the pressure applied edge portions thereof.

4. An article of reed fabric curved in two planes transverse to each other, the fabric being held under different degrees of endwise compression, thus producing bowing in one direction of the stakes, and a bowing transverse thereto of the fabric.

5. An article of reed fabric curved in two planes transverse to each other, the fabric being held by a rigid binding strip engaging their ends under different degrees of endwise compression, thus producing bowing in one direction of the stakes, and a bowing transverse thereto of the fabric.

6. The method of producing a reed canopy or the like that consists in providing a piece of reed fabric with the opposite edges thereof formed along curved lines, holding the fabric against movement as a whole, applying pressure edgewise thereof thereby substantially straightening said curved edge and moving part of the fabric out of its plane of weave into arch-like form, applying pressure edgewise to the fabric in an opposite direction, thereby substantially straightening the other edge and moving the other part of the fabric out of its plane of weave and into arch-like form, and in securing the fabric against reversion to its initial form.

In testimony whereof, I have hereunto set my hand, this 26th day of July, 1920.

MARSHALL B. LLOYD.

Certificate of Correction.

It is hereby certified that in Letters Patent No. 1,412,623, granted April 11, 1922, upon the application of Marshall B. Lloyd, of Menominee, Michigan, for an improvement in "Reed Articles and Methods of Producing Same," an error appears in the printed specification requiring correction as follows: Page 2, line 72, claim 2, for the word "reformed" read *preformed*; and that the said Letters Patent should be read with this correction therein that the same may conform to the record of the case in the Patent Office.

Signed and sealed this 7th day of November, A. D., 1922.

[SEAL.]

KARL FENNING,

Acting Commissioner of Patents.
